HYDROSTATICALLY CONTROLLED ARMING SWITCH

David S. Muzzey, Jr., Washington, D. C., assignor to the United States of America as represented by the Secretary of the Navy

Application May 12, 1952, Serial No. 287,410

4 Claims. (Cl. 102—16)

(Granted under Title 35, U. S. Code (1952), sec. 266)

The invention described herein may be manufactured and used by or for the Government of the United States of America for governmental purposes without the payment of any royalties thereon or therefor.

This invention relates to an arming switch for a mine and more particularly to a hydrostatically controlled time delayed means for closing a switch in the firing circuit of a mine.

Heretofore, in providing for delayed arming of a mine, it has been the practice to incorporate a spring wound clock mechanism having cam means to close the arming switch in the firing circuit of a mine. Such devices employ an initially wound spring and for this reason may prematurely arm the mine if the escapement mechanism should be prematurely released.

The present invention overcomes the difficulties referred to by providing a hydrostatically controlled switch by means of which a time delay of from one to two weeks is possible. A diaphragm in response to water pressure thereagainst forces a piston having a rack mounted thereon downwardly. The rack engages a pinion which through a suitable gear train is provided with an escapement. Adjacent the lower end of the rack member is provided a pair of spaced spring pressed contacts which normally engage an insulated end portion of the rack member. When the water pressure against the diaphragm causes the rack member to move inwardly at a speed determined by the gear train of the escapement the metallic portion of the rack member bridges the contact members thereby completing the arming circuit in the mine. It can be seen, therefore, that the presently disclosed device provides a means for closing an arming switch in the firing circuit of a mine in time delayed relation to the laying of the mine.

A primary object of this invention is to provide a new and improved hydrostatically operated means for closing an arming switch in the firing circuit of a mine in time delayed relation.

A further object of this invention is to provide a piston in a mine which is adapted to be moved inwardly by water pressure thereagainst to close an arming switch and in which the rate of movement thereof is controlled by a gear train and escapement mechanism.

Still another object of the present invention is to provide a means for closing an arming switch in a mine which is relatively simple in construction and economical to produce.

Other objects and many of the attendant advantages of this invention will be readily appreciated as the same becomes better understood by reference to the following detailed description when considered in connection with the accompanying drawings wherein:

Fig. 1 is a sectional view through a mine showing the present invention; and

Fig. 2 is a sectional view along the line 2—2 of Fig. 1.

Referring now to the drawings wherein like numerals indicate like parts throughout the several views there is shown in Fig. 1 the body of a mine 1 which is provided

2

with a circular bore 2. Slidably disposed within this bore is a piston 3 having a rack portion 4 integral therewith which is guided by flanged portions 5 of the body of the mine. A diaphragm 6 is suitably secured around the periphery of the bore to the body of the mine and provides an effective sealing means for the mechanism. The piston is preferably urged outwardly by a flexible spring 16 having one end thereof disposed within an annular recess with the piston and the outer end in engagement with a fixed plate 17 having an aperture therein within which the rack 4 is disposed. The rack member 4 is engaged by a pinion 7 (Fig. 2) to which is secured a gear 8, the shaft 9 of both gears being suitably journalled in the body of the mine. Gear 8 through gear train 10 drives escape wheel 11 which is engaged by a pallet 12, schematically shown in Fig. 1.

Suitably secured to a flange 13 and flange 5 on the body of the mine is a pair of spaced contact members 14 which are spring urged into engagement with rack 4. The lower end portion 15 of rack 4 is insulated so that when the piston and rack member are in the position of Fig. 1 the circuit of contacts 14 is open. When the mine is laid, however, water pressure acting against diaphragm 6 causes piston 3 and rack 4 to move inwardly in time delayed relation determined by the gear train 10 and escapement. When the rack 4 has moved inwardly the metallic portion of this member bridges contacts 14 thereby completing the circuit.

Whereas in the illustrated embodiment of the invention, the contact members are closed by a complementary contacting portion of the slideable rack member, it will be understood, that, if desired, other switching elements may be employed. For example, the switch element may be closed by a cam member actuated by the gear train of the escapement mechanism and operable when the piston has reached the end of its travel or, alternatively, a cam surface or detent may be secured to the rack for closing a switch by movement of the switching elements thereof as the piston travels to the limit of its inward movement.

It is apparent that there has been provided a means for closing a switch in time delayed relation and operable by hydrostatic pressure. The time delay may be varied by changing the gear ratio employed, by varying the inertial mass or moment of the pallet member or the number of teeth on the escapement wheel or by any other suitable means.

While the device has been described for use in closing the arming circuit of a mine in time delayed relation it can be seen that the present invention has utility in any underwater device wherein it is desired to provide a time delay.

Obviously many modifications and variations of the present invention are possible in the light of the above teachings. It is therefore to be understood that within the scope of the appended claims the invention may be practiced otherwise than as specifically described.

What is claimed as new and desired to be secured by Letters Patent is:

1. In a device of the class disclosed, a mine having a bore therein, a diaphragm secured to the periphery of said bore, a piston having a rack member mounted thereon slidably disposed within said bore and movable by said diaphragm from an initial position to a circuit closing position, normally open, switch means mounted within said bore and having a pair of mutually spaced contacts normally in an open condition and closed as the rack member moves into said switch closing position, said rack member and piston being movable inwardly a predetermined amount to close said contacts in response to water pressure against said diaphragm, means carried by said rack member in engagement with said pair of con-

tacts for maintaining the contacts in said open condition until said rack member and piston are moved said predetermined amount, and escapement means operatively connected to said rack member for retarding inward movement thereof in such manner that the switch means is closed at the expiration of a predetermined period of time.

2. In a device of the class disclosed for use in a mine having a bore therein, a diaphragm secured to the periphery of said bore, a switch comprising a pair of normally open mutually spaced contacts mounted within said bore, a piston including rack means thereon disposed adjacent said diaphragm and having insulating and conducting portions thereon disposed within said bore and movable a predetermined amount therein, said insulating portion normally engaging said pair of spaced contacts for maintaining the contacts normally open until said rack means is moved a predetermined amount, said rack means being moved said predetermined amount by said diaphragm in response to water pressure thereagainst wherein the contacts are closed as said conducting portion on the rack means bridges said spaced contacts, and escapement means operatively connected to said rack means for retarding the inward movement of said rack means.

3. In a device of the class described, a mine having a bore therein, a diaphragm secured to the periphery of said bore and having an annular depression formed therein, a movable piston normally disposed adjacent said diaphragm within said bore and having an annular recess for receiving said depression, a rack member integral with said piston and movable therewith, a pinion engaging said rack member, escapement means engaging said pinion and retarding movement of said rack member and piston, said movement being caused by hydrostatic pressure against said diaphragm, switch means mounted within said bore and having a pair of contacts normally in an open position, an insulating member on said rack

member for maintaining the contacts in said open condition until said rack member has been moved a predetermined amount, and a conducting portion on said rack member for closing said contacts when the rack member has moved said predetermined amount.

4. In a device of the class described, a mine having a bore therein, a diaphragm secured around the periphery of said bore and having an annular depression formed therein, a piston having a rack member integral therewith slidably disposed within said bore and having an annular recess formed therein for receiving said depression, said rack member having conducting and insulating portions, switch means comprising spaced contact members spring pressed into engagement with said rack member, said contact members normally engaging the insulating portion of said rack member for maintaining said contact members in an open condition until said piston and rack member are moved a predetermined amount, a pinion engaging said rack member, and escapement means engaging said pinion and actuated thereby for retarding the movement of said rack member, hydrostatic pressure against said diaphragm causing inward movement of said piston and rack member said predetermined amount in time delayed relation determined by said escapement means whereby the conducting portion of said rack member bridges said contact members and closes said switch.
